UNITED STATES PATENT OFFICE.

FORREST H. MURRAY, OF CAMBRIDGE, MASSACHUSETTS.

ARC-DESCRIBING INSTRUMENT.

1,427,493.

Specification of Letters Patent. Patented Aug. 29, 1922.

Application filed July 3, 1920. Serial No. 393,891.

To all whom it may concern:

Be it known that I, FORREST H. MURRAY, citizen of the United States of America, and resident of Cambridge, in the county of 5 Middlesex and State of Massachusetts, have invented new and useful Improvements in Arc-Describing Instruments, of which the following is a specification.

My invention relates to instruments for 10 describing arcs and is particularly adapted for draftsman's use. The object of the invention is to provide a draftsman's instrument which although compact in its proportions is capable of drawing with accuracy 15 arcs of circles of any radius greater than that within the range of ordinary compasses up to infinity. In the drawings here-to annexed which illustrate instruments which exemplify my invention,

20 Fig. 1 is a view in perspective of one form of arc describing instrument;

Fig. 2 is a diagram illustrating the principle of operation of the instrument shown in Fig. 1;

25 Fig. 3 is a view in perspective of another form of instrument; and

Fig. 4 is a diagram illustrating the principle of operation of the instrument shown in Fig. 3.

30 Referring first to Fig. 1. A represents a frame which will preferably be made of metal, and in this frame slide-ways D are formed in which the legs L, L' are slidably and adjustably mounted. The legs are 35 properly confined in their slide-ways by means of metallic covers B in which are mounted set screws C which bearing on the legs L, L' in the slide-ways D serve to fix the said legs at any desired degree of ex-

40 tension from the frame A. The outer and lower ends of the legs L, L' are suitably pointed. An arm R is mounted in the frame A pivotally with respect to said frame and therefore with relation to the legs L, L'.

45 The pivotal mounting of the arm R is by means of shaft S to which the arm R is attached, adapted to carry a line drawing instrument such as I. This instrument will preferably be rotatably adjustable on the 50 arm R as by means of the offset bracket F which is provided with a clamp as at F' with which it may be set at any desired angle about the axis of the arm R. This rotatable adjustment will enable the drawing instrument I to be set in proper relation to the 55 paper on which an arc is to be described.

If the extension of the legs L, L' from the frame A be such that the axis of the shaft S is parallel with a straight line passing through the points of the legs L, L', and 60 the frame A be then rocked on that line as an axis, it is obvious that the line drawing instrument I if allowed to rest upon the paper and to move over it will describe a straight line. If however, the instrument be 65 so adjusted that the axis of the shaft S which is the pivotal axis of the arm R stands at an angle greater than zero with a straight line passing through the points L, L', a rocking movement of the frame A 70 will cause the line drawing instrument I to move in the arc of a circle. Referring to Fig. 2: The legs of the instrument may be so adjusted that the leg L extends further from the frame than the leg L' and the 75 frame therefore resting on the points of these legs is tilted and a line drawn in prolongation of the axis of the shaft S will intersect the straight line passing through the points of the legs L, L' at the point O; this 80 point is the center of the circle, will be the distance V between the instrument I and the center O. This radius V may be varied in length from the minimum prescribed by the proportions of the instrument itself and 85 infinity.

Referring now to Fig. 3 the frame a of the instrument is generally circular in form and is provided with lugs a³, a⁴ in which the legs l, l' are fixed, these legs extending 90 equally from the frame. The frame is not completely circular but is segmental so that the arm r may swing from one side of the frame to the other through the gap in the frame. This arm is pivotally mounted by 95 being secured to a shaft s, which is journaled in the segmental slide h. The slide h lies in an annular channel formed on the inside of the frame a, one side of said channel being provided by the segmental cover plate a' secured by means of set screws a² to the frame a so that it performs the function of a clamp to hold the segmental slide h in any 100 desired position. The line drawing instrument i is mounted and rotatably adjustable 105 on the arm r. By slackening the set screws a² the segmental slide h may be made to assume any desired angle (within the structural limits of the instrument) with a straight line passing through the pointed 110 ends of the legs l, l', and thus as in the case of the instrument shown in Fig. 1 the line

5 drawing instrument *i* may be made to describe the arc of a circle and the radius of this circle may be varied from the minimum prescribed by the structural limitations of 10 the instrument to infinity.

15 Referring to Fig. 4: the shaft *s* is shown adjusted at such an angle to the line passing through the ends of the legs *l*, *l'* that geometrical prolongation of the axis of the shaft intersects the said straight line at the point *o*; this point is the center of the circle of which the instrument *i* will describe an arc as the frame *a* is rocked or turned about the line passing through the points of the 20 legs as an axis. The radius of that circle is indicated by *v*.

I claim:—

1. In an arc-describing instrument, a frame adapted for angular movement about 25 an axis, an arm, adapted to carry a line-drawing instrument, mounted in pivotal relation to the frame, the said arm and frame being relatively adjustable to vary the angle between the pivotal axis of the arm and the axis of angular movement of the frame.

2. In an arc-describing instrument, the combination of supporting means including 30 a pair of legs, an arm, adapted to carry a line-drawing instrument, mounted in pivotal relation to the supporting means, the said arm and legs being adjustable relatively to each other to vary the angle between the pivotal axis of the arm and the straight line passing through the ends of the legs.

3. In an arc-describing instrument, the combination of a frame, a pair of legs attached to the frame, a shaft pivotally mounted in the frame, an arm on the shaft adapted 40 to carry a line-drawing instrument, the legs and shaft being adjustable relatively to each other to vary the angle between the axis of the shaft and the straight line passing through the ends of the legs.

4. In an arc-describing instrument, the 45 combination of a frame, a pair of legs

mounted in the frame, a shaft pivoted in the frame, an arm on the shaft adapted to carry a line-drawing instrument, the said legs being adjustable to vary their relative extension from the frame.

5. In an arc-describing instrument, the combination of a frame, a pair of legs 50 slidably and adjustably mounted in the frame, a shaft pivoted in the frame, and an arm on the shaft adapted to carry a line-drawing instrument.

6. In an arc-describing instrument, the combination of a pair of legs, an arm mounted in pivotal relation to the legs, a line-drawing instrument mounted and rotatably 55 adjustable on said arm, the said arm and legs being relatively adjustable to vary the angle between the pivotal axis of the arm and the straight line passing through the ends of the legs.

7. In an arc-describing instrument, the combination of a frame including a pair of legs, a shaft pivoted in the frame, an arm on the shaft, a line-drawing instrument mounted and rotatably adjustable on the arm, the 60 shaft and frame being adjustable relatively to each other to vary the angle between the axis of the shaft and the straight line passing through the ends of the legs.

8. In an arc-describing instrument, the combination of a frame, a pair of legs mounted in the frame, a shaft pivoted in the frame, an arm on the shaft, a line-drawing instrument mounted and relatively adjustable on the arm, the said legs being adjustable to 65 vary their relative extension from the frame.

9. In an arc-describing instrument, the combination of a frame, a pair of legs slidably and adjustably mounted in the frame, a shaft pivoted in the frame, an arm on the shaft, and a line-drawing instrument mounted and rotatably adjustable on said arm.

Signed by me at Boston, Massachusetts, 70 this first day of July, 1920.

FORREST H. MURRAY.
